Frank H. Allen

ATTORNEY.

UNITED STATES PATENT OFFICE.

GEORGE W. WATSON, OF BOSTON, MASSACHUSETTS.

NON-SLIP HEEL FOR FOOTWEAR.

1,350,190.

Specification of Letters Patent. Patented Aug. 17, 1920.

Application filed June 20, 1919. Serial No. 305,537.

To all whom it may concern:

Be it known that I, GEORGE W. WATSON, a citizen of the United States, residing at Boston, in the county of Suffolk, in the State of Massachusetts, have invented a certain new and useful Improvement in Non-Slip Heels for Footwear, of which the following is a specification, reference being had to the accompanying drawings.

10 This invention relates to removable attachments for the heels of footwear which will effectually prevent such footwear from slipping on icy places; my purpose being to provide an extremely simple and cheap device which will be practically invisible and which may be quickly attached to or removed from a shoe without the aid of screws, straps or other fastenings.

Heretofore it has been quite common to 20 use spurs or other metallic devices which have been strapped or screwed to the heels or soles of footwear but such devices can be utilized only on icy places whereas my present non-slip device may be worn everywhere, 25 even on highly polished floors, without injury to either the said devices or to such floors; thus rendering it unnecessary to remove the non-slip devices before going indoors.

30 The drawings annexed hereto illustrate my invention, Figure 1 being a side view of a shoe, having attached thereto a non-slip device of my present improved construction.

Fig. 2 is a perspective view of said device 35 and Fig. 3 is a central, vertical, sectional, view of the same.

My invention, briefly described, consists of an elastic cap which is adapted to fit snugly on a shoe heel, the construction of 40 said cap being such that it will be securely fastened to the heel so long as it is required for service and so that it may be readily removed when it is no longer required for non-slip purposes.

45 In the drawings the shoe is indicated by the reference letter *a*. My improved non-slip attachment is of general cup construction, conforming to the size and shape of the shoe heel and the adjacent portion of the 50 shoe counter. Described more specifically, the lower portion *b*, is shaped to fit tightly on the shoe heel, and the upper or rim portion *c*, is flared to conform to the shape and size of the counter of the shoe, said upper, 55 rim, portion being cut down at its front por-

tion *c'* almost to the point where the heel joins the upper.

The tread portion of the described non-slip device is corrugated transversely, as at *d*, to further prevent the undue slipping of 60 the device, and in order to prevent the device from accidentally slipping off from the shoe heel, I locate in the front wall *e* an indented portion *f* which will yield to permit the device to receive and fit tightly upon heels of 65 different lengths, as will be understood by reference to Fig. 1 of the drawing.

In the operation of drawing the non-slip cap onto the shoe, said cap is first positioned as seen in dotted outline in Fig. 1, that is to 70 say with the upper edge of the front *e* located at the angle where the said front joins the sole of the shoe; the cupped upper portion of the device being then drawn upward into engagement with the counter of the 75 shoe, as seen in full lines in said Fig. 1. As the device is thus moved to its operative position on the shoe, the indented portion *f* is forced into close engagement with the front of the heel sufficiently to prevent the device 80 from slipping downward, away from the heel, so long as the cupped portion *c* remains in engagement with the shoe counter.

My described improvement may be manufactured very cheaply and attached to the 85 shoe quickly and, by its use, many falls, and serious accidents resulting therefrom, will be prevented.

My invention is particularly distinguished from similar devices as previously constructed by providing means whereby the rear part of the resilient heel cap or pocket is caused to snugly fit the heel and counter, thereby doing away with the liability of loosely fitting pockets being easily torn and 90 ripped open at this part of the shoe which is most exposed to injuries and strains, the loose fit in my invention being provided at the breast part of the heel by means of an inwardly projecting shoulder in spaced relation with the juncture of the heel breast with the shaft of the sole.

Having thus described my invention, I claim:—

1. In a device of the character described 105 in combination a heel, a heel inclosing pocket of resilient material and adapted to snugly fit the rear part of said heel, and inwardly concaved, cup shaped, resilient projecting means at the front wall of said pocket, and 110

- adapted to rest against the breast of said heel.
2. In a device of the character described in combination a heel, a shoe counter connected to the upper part of said heel, a heel-and-counter inclosing pocket of resilient material, the rear part of said pocket substantially corresponding in shape to the shape of said heel and counter, and adapted to snugly fit said heel and counter, and inwardly projecting means at the front part of said pocket in spaced relation to the open end of said pocket, and adapted to engage with the breast of said heel.
3. In a device of the character described in combination a heel, a shoe counter connected to the upper part of said heel, a heel-and-counter inclosing pocket of resilient material, the rear part of said pocket being shaped to substantially correspond to the 20 shape of the rear part of said heel and of said counter, and a straight front wall on said pocket, and an inwardly projecting shoulder on said front wall in spaced relation to the open end of said pocket, and 25 adapted to rest against the breast of said heel.
4. In a device of the character described in combination a heel, a counter portion at the upper rear part of said heel, an open 30 mouthed resilient, heel-inclosing pocket, the inwardly smooth rear part of said pocket snugly engageable with the rear part of the heel and of the counter portion, and an inwardly concaved projection at a distance 35 from the edge of said pocket opening and engageable with the heel breast.

GEORGE W. WATSON.
